UNITED STATES PATENT OFFICE.

WILLIAM H. MOTTER, OF DENVER, COLORADO, ASSIGNOR TO MARY A. MOTTER.

ORE-ROASTING FURNACE.

1,172,479.

Specification of Letters Patent. Patented Feb. 22, 1916.

Application filed May 18, 1913. Serial No. 768,559.

To all whom it may concern:

Be it known that I, WILLIAM H. MOTTER, a citizen of the United States, and a resident of the city and county of Denver, 5 State of Colorado, have invented certain new and useful Improvements in Ore-Roasting Furnaces; and I do declare the following to be a full, clear, and exact description of my invention, such as will enable 10 others skilled in the art to which it appertains to make and use the same, reference being had to the accompanying drawings, and to the figures of reference marked thereon, which form a part of this specification. 15

My invention relates to improvements in ore roasting furnaces and has for its object the provision of a machine of this character which will produce a uniform and 20 efficient oxidation of the ore.

Other objects of my invention reside in the particular arrangement of elements and combination of parts which will be herein-after fully explained by reference to the 25 accompanying drawings.

In these drawings Figure 1 is a side elevation view of my improved ore roasting furnace; Fig. 2 is a longitudinal section through the front end of the machine; Fig. 30 3 is a sectional view through the rear end of the machine; Fig. 4 is a cross section through the roasting cylinder; and Fig. 5 is a detail view of the joint of the sections composing the cylinder.

Corresponding and like parts are referred 35 to in the accompanying drawings by the same reference characters.

Let the numeral 5 designate a cylinder composed of a plurality of sections 6, 7, and 40 8. Sections 6 and 7 of the cylinder are composed of two walls 9 and 10, the said walls being separated from each other and forming an air space or flue space through which the products of combustion pass.

The inner wall 10 of the sections is connected with the outer wall 9 by means of 45 arms 12. In other words these arms 12 connect with a ring 13, which is provided with laterally extending flanges 14, upon which 50 the outer wall is supported. The circumference of this ring 13 extends beyond the outer wall of the cylinder as shown at 14'. Each extremity of each section 6 and 7 is constructed in this manner, whereby when 55 the sections are put together in alinement

the rings 13 abut together and bolts 15 are passed there-through for securing the said sections together. The outer walls 9 of the sections rest upon the shoulders or flanges 14, the said flanges or shoulders serving to 60 support the said outer wall in position. The outer wall of each of the sections 6 and 7 is composed of sheet metal 16, lined with asbestos 17. The sheet metal parts 16 of each section are composed of two longitudinal halves 18 and 19, which overlap at their edges 20 and are secured together by means of bolts 21, passing through angle members 22. By tightening these bolts 21, the two halves 18 and 19, composing the sections 65 may be tightly drawn together and made to firmly and rigidly clasp or engage with the flanges or shoulders 14. The parts 14 of the rings 13, which extend beyond the outer wall of the cylinder, form tracks 70 which engage rollers 23, 24 and 25. The rollers 23 and 24 are mounted upon a shaft 26, the said shaft being journaled in supports 26. The extremities of the cylinder 75 are respectively journaled in housings 28 and 29, the housing 28 composing a part of the flue, while the housing 29 forms the firebox.

The fire-box is designated by the reference character 30, while the flue is designated by 80 the reference character 31. The outer wall 9 of the cylinder stops with the flue 31, while the inner wall 10 of said cylinder continues on through the flue 31 as shown at 32. The interior of the inner wall 10 of the cylinder 90 is provided with spiral flanges 33, which flanges extend entirely through the cylinder. A tubular member 34 is partially inserted into the forward end of the cylinder through 95 an opening 35. Within the tubular member 34 I journal a feed screw 36. The axis of this feed screw 36 extends beyond or exteriorly of the tube 34 and is journaled in a boxing 37. A sprocket wheel 38 is mounted upon the axis of this feed screw 36 and a 100 sprocket chain 39 is passed around said sprocket wheel 38 and around a similar sprocket wheel 40 mounted upon shaft 26. Thus by this arrangement power will be 105 transferred from the shaft 26 to the feed screw 36, whereby the latter will be operated for feeding the ore or other material to be roasted into the roasting cylinder. A feed hopper 41 is arranged in communication 110 with the interior of the tube 34, and through

this feed hopper 41 the ore or material passes into the tube 34, where it is taken up by the feed screws 36 and carried into the cylinder.

A gear wheel 42 is mounted upon the cylinder, the said gear wheel 42 entirely surrounding said cylinder and meshing with a pinion 43. A shaft 44 is journaled in journal boxes 45, said shaft 44 being provided with a gear 46, which meshes with a gear 46' 10 adapted to transmit power to the pinion 43. Also mounted upon this shaft 44 is a cone pulley 47, adapted to accommodate the motor belt. Power is transmitted to the gear wheel 42, to cause the cylinder to revolve, 15 through the medium of this cone pulley 47, shaft 44 and pinion 43. Thus the cylinder is caused to revolve and engagement of the latter with the rollers 23 and 24 causes the shaft 26 to revolve, which transmits power 20 to the feed screw 36 for operating the latter. During the revolving of the cylinder the ore is deposited in the latter by the feed screw 36 and the spiral flanges 33 cause the ore to gradually and uniformly travel through the 25 cylinder. These flanges 33 serve to uniformly distribute the ore, whereby the latter is thoroughly exposed to the influence of the heat.

By referring to Fig. 1 of the drawings it 30 will be seen that the inner wall 10 of the cylinder terminates at a certain distance from the rear end, however, the outer wall 9 of the cylinder being continued. This continuation of the outer wall 9 of the cylinder forms the 35 section that has been designated 8 in Fig. 1 of the drawing. The wall composing this portion of the cylinder or section 8 of the latter is lined with fire-clay material 48, having flanges of spiral shape 49 arranged there- 40 in. It is necessary to line this section 8 with fire-clay, since this section is the closest to the furnace and is subjected to very intense heat which would result in injury to this portion of the cylinder were it not for the 45 fact that the latter is lined with the fire-clay. The ore or material is fed by the spirals 49 of this section into a chute 50, through which chute the ore or material is deposited upon a conveyer 51, by means of which the said 50 ore or material is carried to any suitable place of deposit.

An air pipe 52 passes through section 8 of the cylinder, said air pipes forming a spider and supporting a centrally located bell 53. This bell 53, of course, communicates with the interior of these air pipes 52, the said bell 53 being arranged directly in front of the extremity of the roasting member of the cylinder, whereby the air from the air 55 pipes 52 is directed into the inner wall or roasting member of the cylinder, while the shape of the bell serves to prevent the products of combustion from passing through the inner wall or roasting member of the cylinder, but on the contrary said bell directs 60

the smoke and product of combustion through the space between the two walls of the cylinder. The outer extremities of the air pipes 52 are provided with caps 54, which caps are adjustable to control or regulate the amount of air admitted into said pipe. In other words these caps 54 are slidably mounted in the outer extremities of the pipes 52, the said caps being provided with openings or slots 55 through which the air passes. These pipes 52 are held in place within section 8 of the cylinder by means of nuts 56, inserted upon the outer extremities of said pipes in engagement with washers 57. By virtue of these air 70 pipes 52 arranged within section 8 of the cylinder, the air in passing through said pipes will be heated before the air comes into contact with the ore or material within the furnace. Thus the air will have no 75 negative influence upon the roasting ore within the cylinder. The air from the pipes 52 passes through the bell 53 into the roasting member of the cylinder, passing through the latter and into a dust chamber 58, 80 through the opening 35. From this dust chamber 58, the air passes through a downwardly inclined pipe 59 into a baffled chamber 60. The air circulates through the chambers of this baffled chamber as indicated by 85 the arrows, and then through a pipe 61 into a water tank 62. The air in passing through the cylinder, the dust chamber 58, pipe 59, and baffled chamber 60, allows the dust carried thereby to settle in said dust chambers 90 the volatile matter being carried through said chambers and forced into the water of the tank 62, by means of a fan 63, which is arranged in the pipe 61. A section 63 of the pipe 61 passes into the water tank 62 and 95 extends into the water of the latter. This section 64 of the pipe 61 is composed of clay or other material which will not be effected by the acid. This section 64 is supported by means of a flange 65, resting on top of the 100 water tank. By inclining the pipe 59 downwardly, any dust which may settle in said pipe will pass into the baffled chamber 60 under the influence of gravity.

A plate 66 is bolted to a flange 67 formed 115 on the forward end of the part 32 of the cylinder. This plate 66 is provided with a thimble 68, which forms the opening 35 heretofore referred to. This thimble 68 is received in a similar thimble 69 formed 120 upon the dust chamber 58. The section 32 of the cylinder is of greater diameter than the opening 35, whereby a flange or rim 70 is formed at the rear end of the section 32, which prevents the ore or material deposited 125 in said section 32 by the feed screw 36, from passing rearwardly through the opening 68.

The space between the two walls 9 and 10 of the cylinder, as heretofore explained, forms a flue space for the smoke and products 130

of combustion to pass through from the fire-box 30. By reason of the fact that the outer wall 9 is lined with asbestos, the outer cold air is prevented from affecting the temperature in the flue space. In other words the heat from the fire-box is retained within this flue space and its influence imparted to the ore within the roasting member of the cylinder.

10 The fan 63 serves to create a suction which results in drawing the air through the roasting member of the cylinder from the bell 53. Thus volatile matter is carried through this cylinder with the air, some of said dust and volatile matter settling in the dust chamber 58, while another portion of it passes through the baffled chamber 60 and any remaining dust or volatile matter is forced under water in the tank 62 where the 20 remaining valves are precipitated. I provide doors 71 in the baffled chamber 60 through which the dust may be removed from said chamber. By reason of the fact that the roasting member of the cylinder 25 passes through the chamber 31, forming a portion of the flue space, the dust and volatile matter is prevented from escaping through the flue.

While I have illustrated and described 30 herein a specific form of my invention it is understood that I am not limited thereto and that the same may be varied and modified without departing from the spirit of my invention or the scope of the appended 35 claims.

Having thus described my invention what I claim and desire to secure by Letters Patent is:—

1. A furnace, comprising a cylinder composed of an inner member and an outer member supported around the inner member and leaving a space between said members, the outer member having a part extending beyond the inner member, a transverse pipe passing through said part and communicating with the exterior of the latter, a bell-member arranged in front of the inner member and supported by said pipe, said bell-member being in communication 45 with said pipe, and a fire-box with which said part is in communication.

2. A furnace of the class described, comprising a cylinder composed of an inner member and an outer member supported around the inner member and leaving a space between said members, the outer member having a part extending beyond the inner member, transverse pipes arranged in said part and communicating with the exterior of the latter, means controlling the outer extremities of said pipes for regulating the admittance of air therein, a member supported by said pipes on the interior of said part and arranged in front of the inner member, said member directing the air

into the inner member of said cylinder, a fire-box with which said part is in communication, and said bell directing the products of combustion into the space between the two members of said cylinder.

3. A furnace, comprising a cylinder composed of an inner member and an outer member supported around the inner member and leaving a space between said members, the outer member having a part extending beyond the inner member, a fire-box with which said part is in communication, said part being lined with fire clay having flanges formed thereon, a transverse pipe passing through said part and communicating with the exterior of the latter, adjustable caps controlling the outer extremities of the said pipe, and a member in communication with said pipe on the interior of said part, said member being arranged to discharge into the inner member of said cylinder, and to deflect the product of combustion into the space between the two members of said cylinder.

4. A furnace, comprising a cylinder composed of an inner member and an outer member, supported around the inner member and leaving a space between said members, the outer member having a part extending beyond the inner member, pipes passing through said part and communicating with the exterior of the latter, the said pipes having a member in communication therewith on the interior of said part, the said pipes being adapted to admit oxygen into the inner member of the cylinder for creating a suitable roast of the ore such as is required for subsequent treatment of the latter, and a fire-box with which said pipe is in communication.

5. A furnace, comprising a cylinder composed of an inner member and an outer member, supported around the inner member and leaving a space between said members, the outer member having a part extending beyond the inner member, a fire-box with which said part is in communication, transverse pipes passing through said part and communicating with the exterior of the latter, and a bell-member arranged on the interior of said pipe and in communication with said pipe.

6. A furnace, comprising a cylinder composed of an inner member and an outer member, supported around the inner member and leaving a space between said members, the outer member having a part extending beyond the inner member, transverse pipes arranged in said part and communicating with the exterior of the latter, adjustable caps controlling the outer extremities of the said pipes for regulating the admittance of oxygen according to the character of roast desired, said pipe being in communication on the interior of said

part with the inner member of the cylinder, and a source of heat with which said part is in communication.

7. An ore roaster, comprising a cylinder forming a roasting member and a flue member, said cylinder being formed with a plurality of sections, each of said sections having a flange on its extremity, other flanges carried by said first named flanges 10 extending at right angles to the latter and supporting the flue member around said roasting member, bolts passing through said first named flanges for securing said sections together, said first named flanges being so 15 located as to provide spaces between the roasting member and the flue member, and rollers upon which said cylinder is revolvably mounted, said rollers being engaged by said flanges of the sections composing 20 said cylinder.

8. An ore roasting furnace, comprising a cylinder composed of a roasting member and an outer flue member, both of said members being composed of a plurality of sections, the extremities of the sections of the roasting member having rings supported thereon and there being a space between said rings and said sections, laterally arranged flanges on said rings, the sections of the flue member being engaged by said flanges and supported around the roasting member by the same, the space between the two members forming a flue space, and a fire box with which said flue space is in communication. 25 30 35

In testimony whereof I affix my signature in the presence of two witnesses.

WILLIAM H. MOTTER.
